GAME FOR USE IN CONNECTION WITH A PATTERN FORMING CORD

Martin Radt, New York, N. Y.

Application March 27, 1953, Serial No. 345,037

2 Claims. (Cl. 35—30)

This invention relates to an educational game.

In combination with its amusing, interesting and practically inexhaustible playing capacity the invention has the great merit to teach the user and particularly children how to accurately add and subtract figures.

Another intriguing property of the invention consists therein that the manipulation of the game is of a self-correcting type.

A further feature of the invention is based upon the wide range of varying the playing mode of the game.

The invention will now be described more in detail and with reference to the attached drawings.

In the drawings

Fig. 1 is a top view of the game,

Fig. 2 is a side view thereof,

Figs. 3, 4 and 5 are top diagrammatic views of star-shaped pictures producable by playing the game.

As apparent from Figs. 1 and 2 the game comprises a flat and preferably quadrangular base *a*, which may be preferably made of wood or plastics.

Pins *b* of which the number conforms to a prime number, for instance to 11, are circularly stationed on the base *a*. The pins are denoted by numbers 1–11 and, at the same time, 12–22, see Fig. 1, and so forth and may preferably have an equal distance from each other.

In playing the game a preferably elastic cord *c* is used, which is provided with a small loop *d* at its one end. This cord may preferably be wound on a spool *e* in order to eliminate its being tangled up during the playing of the game. It is advisable to use a spool having an inside spring which will automatically retract the cord during the time it is not used.

The cord *c* is with its loop *d* applied to one of the pins located on the base, for instance, pin 1.

In order to create a star-shaped picture the cord *c* is conducted from pin 1 to another pin located, for instance, on the opposite side of the circular pin arrangement, such as number 5, as apparent from Fig. 3. The difference between any two numbered pins between which the cord extends will be denoted as a "step." Since in the given example the difference in the numbers between pin 1 and pin 5 is 4, the step is here 4. In the given example the step is kept constant so that the cord is successively conducted over the pins 1, 5, 9, 2, 6, 10, 3, 7, 11, 4, 8, 1. The starting pin, 1, is reached again and a star-shaped picture is thus completed as shown in Fig. 2.

It is advisable to apply different colors to the base and to the cord whereby the attractiveness of the produced star is increased.

The number 11 is, by way of example, chosen for the number of the pins, however any other prime number may be used for this purpose.

The pins *b* may be replaced by hooks, pegs, nails, screws or other suitable upright means adapted to removably hold the cord *c*.

The game is, as already indicated above, based on the condition that the number of the pins must be a prime number such as 5, 7, 11, 13, 17, 23, 37, and so forth.

2

The distance between the pins over which the cord is conducted will be, as stated above, denoted as a "step." This step equals in the case of Fig. 1 the distance between the pins 1 and 5, that means 4. It might be maintained in passing from one to another pin, for instance, in the shown example from pin 1 to 5, from pin 5 to 9, from pin 9 to 13 which is also pin 2, and thereafter to pins 6, 10, 3, 7, 11, 4, 8, finally returning to pin 1. In this case the star shown in Fig. 3 is completed with the result that each pin was only once touched by the cord *c*. However, the playing of the game is not conditioned on the maintenance of equal steps.

It is interesting to note that the steps may comprise any pin distance except the one corresponding to the entire number of the pins which in the case of the shown example would be eleven. The child playing the game will always return to pin 1 after once having passed the other pins if starting from pin 1 and using equal steps.

A mathematical proof for the described procedure is, as follows.

A prime number "N" cannot be divided by any other number than by itself and by 1. If the selected step is equal to "A," "N" divided by "A" does not lead to an integer and hence the cord will not return to the starting pin after a single circuit.

Only if the constant step "A" is made "N" times so that the total number of bypassed pins is *A* times *N* will this number, *A* times *N*, be divisible by *A* and after *N* steps the cord return to the starting pin. The cord has completed a number of circuits equal to *A* and each one of the pins has been contacted by the cord once and only once. On the basis of this algebraic principle the use of the game may be considerably enlarged, as follows.

(a) The start from pin 1 is not compulsory and the player may start from any pin he wishes to select.

(b) It is not necessary to lead the cord in the clockwise direction which means practicing addition; the game may also be used in a counter-clockwise manner and the cord may be conducted, for instance, from pin 9 to 6, hereafter to 3 and so on, which would enable the practicing of subtraction.

(c) The use of the game is not restricted to one definite step "A." It is possible to use two different steps "A" and "B." In conformity therewith the rule of using the game may, for instance, be first a step equal to two and thereafter a step equal to five. The pins will be contacted, in this example, in the order 1, 3, 8, 10, 4, 6, 11, 2, 7, 9, 3, 5, 10, 1, 6, 8, 2, 4, 9, 11, 5, 7, 1. A star is thereby created as shown in Fig. 4, which has a different configuration from the one shown in Fig. 3. The main difference consists therein that each pin has been twice engaged. The beauty of the star is thus greatly increased. Just as well as forward the two steps could be taken backward, or one step forward, for instance, two pins, and one backward, for instance, five pins or vice versa.

(d) It is also possible to use 3 or more steps for instance the three steps 2, 3, 5. Hereby each pin will be touched three or more times. Again any number of steps may be forward or backward, for instance, using three steps: 4 forward, 2 backward and again 2 forward; or, for instance, 5 forward, 3 backward and 1 forward.

This procedure will lead to a large number of different configurations. The only rule, however, which must be obeyed is that the sum of the steps must not amount to the number of pins, in the present example not to 11; for instance, steps 2, 3, 6 cannot be used in a forward sequence for 11 pins, as apparent from the figures.

Such an enlarged play rule may, however, be used only by older children or even by adults as it makes the playing of the game more difficult but at the same time more exciting and causes a better entertainment due to its extremely large number of variations.

Older children may devise any additional number of playing rules. With younger children, however, the execution of always one constant forward or backward step is preferable.

Beautiful stars may also be attained particularly by 5 younger children, as follows:

After one star is completed by the application of the one step method the cord is left in its position and another star is formed with a different step and produced on top of the first star. Fig. 5 shows this manner of playing the game by the execution of first constant step 1 and then constant step 5. Hereafter further stars with different steps may be added, whereby a large variety of stars may be produced greatly increasing the beauty of the figures.

The check for a correct addition or subtraction can be automatically established.

(1) By the fact that after return to the starting pin all other pins must have been engaged once in the use of a single-step method or several times if the above referred-to combination step method is used; it is necessary that all pins are engaged an equal number of times.

(2) By the symmetrical shape of the formed star which is apparent on sight.

Since certain changes may be made in the above device 25 and different embodiments of the invention could be made without departing from the scope thereof, it is intended that all matter contained in the above description or shown in the accompanying drawings shall be interpreted as illustrative and not in a limiting sense. 30

I claim:

1. A game for use in connection with a pattern-forming cord comprising a base, and a plurality of uniformly spaced cord-guiding members arranged in a circle upon

said base and being denoted by sequential numbers applied to said base contiguous with said members, the number of said guide-members equaling a prime number so that a pattern forming cord may be step-wise conducted from a freely chosen first guiding member to the other guiding members in sequential order while missing an always equal number of intermediary guiding members until contact has been made with all of them, whereby star-shaped figures are formed by said cord.

10 2. In an amusement device for use in connection with forming a pattern by means of a string, in combination, a base, a plurality of string-guiding members, said members being arranged along the periphery of a circle on said base and each being spaced from the adjoining two mem-

15 bers, the number of members being a prime number, so that a string wound about said members starting in contact with one member and conducted around the other members in a uniformly repetitive pattern of steps which omits the same selected number of pins in each corresponding step of the pattern will produce a symmetrical figure and contact all pins an equal multiple number of times.
